John Bingham & Julius Davis, Inventors & York.

Letters Patent

The Schedule referred to in these Letters Patent, and making part of the same containing a description of the parts of the said John Bingham and Julius Davis themselves of their improvement in the use and application of Steam & the endleß screw and in the apparatus for propelling machinery by steam.

To all whom these presents shall come:

Where it is known that we John Bingham & Julius Davis of Fishers in the County of Onondaga in the State of New York have invented certain new and useful improvement in the use and application of Steam; and the use and application of the endleß screw, and in the machinery and apparatus to be used in propelling machinery by steam of which the following is a description:

First. Said improvement consist in attaching to or connecting with the hollow globe or cylinder formerly invented such machinery as may be necessary to operate all kinds of machinery. Said Globe or cylinder is a metallic Globe or cylinder, similar to that described in the Mechanics Magazine, and is placed upon a hollow metallic shaft and secured with it. Said shaft passing through the center of the Globe or cylinder so that the same may be readily fastened on the shaft. One or more hollow arms ^{take} are inclosed in said Globe or cylinder of equal length and dimensions and balancing each other and on side opposite to each other, and of not a length as may be adapted to the machinery to be moved. These arms or tubes are elongated thinner ends, and have an orifice near the outer ends and on opposite sides of the arms from which the steam issues at right angles with the line of the shaft through which the steam passes into the globe or cylinder, and the steam thus issuing from said orifice produces by its reaction force a revolving motion of the globe or cylinder and shaft. The steam is conducted from the boiler into the end of the shaft by a tube connecting the boiler and the shaft, and through the shaft into the globe or cylinder and from the globe or cylinder

into said arms or tubes — Second. To produce a reverse motion or motion in an opposite direction to that before mentioned two other hollow arms or tubes closed at the ends, as before mentioned and constructed in the same manner and having similar surfaces but opening in directions opposite to those first mentioned are inserted in the globe or cylinder and the steam is conducted from the boiler into the other end of the shaft by another tube and through the globe or shaft to the globe or cylinder, and in this case the globe or cylinder is divided into two compartments or chambers, one of which is connected with the arms or tubes first mentioned and the other with the arms or tubes last mentioned to produce motion in opposite directions. There may be two globes or cylinders placed on the shaft in the manner before mentioned with arms or tubes as before described — having no internal passage for the steam from one to the other, and receiving the steam from the boiler through the opposite ends of the shaft by two distinct tubes. In order to conduct the steam to either end of said shaft so as to produce motion in the desired direction, the tubes through which the steam is conducted from the boiler to the shaft may be inserted in the boiler — case to each other, and a sliding valve may be constructed so when it closes the passage from the boiler through one tube, it opens the other passage, and by half opening one of said passages it will shaft close the other — In the latter case the steam will pass equally from the boiler through each tube to each end of the shaft and into each of the globe or cylinders when there is two (or into each of a pair of chambers of the globe or cylinder when there is but one and divided as before mentioned) and will produce a balance of power and a cessation of motion, and in this situation the steam may be kept on when the motion is stopped without danger of explosion because the steam will continually escape through its several passages.

As the force of the power hereafter mentioned, upon the shaft will have a tendency to move the shaft sideways and to cause friction, in order to balance and counteract that following or friction the surface through which the steam escapes from the arms or tubes may be so placed that the steam will not pass from the tube in a line nearly at right angles

angles with the shaft, but a little obliquely & in addition to give a force opposite to that in which the fire goes against the shaft. Or the friction caused by the same as above mentioned may be counteracted, etc, by balancing by a plate of iron fixed on or near the end of the shaft upon friction setting. And friction setting may be placed under the shaft, working with the globe or cylinder in all cases when necessary to reduce the friction, and also under the shafts of all other wheels. To give motion to the machinery to be moved, an indigo stone is placed upon or near one end of the shaft on which the globe or cylinder is, (or on both ends as circumstances may require) and a wheel, the shaft of which is at right angles with the shaft on which the globe or cylinder is placed, is so placed that the cog or teeth match or mesh with the wheel, and is moved by it as the circumstances require, and one may be placed on or near the end of the shaft of said wheel, and another wheel may be connected with in the manner above described, and any other number of wheels and cogs may be placed and connected together in some convenient manner for the purpose of increasing the power to any desired degree, the effect of which will be to increase the power but to diminish the motion still - & in order to save fuel and to make the greatest use of the heat produced by any given quantity of fuel, a box made of cast iron or some other metal or suitable material may be so placed as to inclose the globe or cylinder and to receive the heat escaping from the furnace and boiler. And this box is so placed that the heat may be let on to the globe or cylinder without letting off through the chimney without going into the cylinder by opening and closing a valve or damper filled into the box for that purpose. The heat being thus let into the globe or cylinder will rarefy and expand the enclosed steam and produce the same power with less fuel. The globe or cylinder may be further heated if necessary or desirable, by making a door in the outer side of said box and by burning coal or other fuel in the box and under the globe or cylinder, or in any other mode that may be deemed expedient.

Trusts, etc the purpose of using the steam after it has performed its office in moving the machinery, and of applying it to other useful purposes

a jacket or box may be made around the globe or cylinder enclosing the iron from which the steam escapes which will receive all the steam which escapes from the engine. A pipe or tube may be inserted into this jacket or box by which the steam may be conducted to any place where it may be wanted for the purpose of warming Rooms, boiling water or any other use to which it may be applied. This jacket or box is to be so placed as to receive the steam without receiving the smoke from the furnace or boiler and so as to prevent the steam from falling back upon the fire. A chimney may be made of cast iron or other suitable material, and so placed as to receive the globe or cylinder and the box made to receive the engine heat and the flame through which the smoke may pass off and the chimney also at pleasure. The furnace in which the globe and cylinder & boiler are placed should be made of cast iron or some other incombustible material and the boiler may be constructed and placed in the common manner, and the heat may be applied in the usual way to the boiler. This Engine and apparatus may be used for propelling boats, & vessels upon the water, for working all kinds of mills and manufactures, for moving carriages on rail roads and on the land; for raising vessels upon marine harbours, and for raising all heavy bodies and for all other purposes to which steam power can be applied. — 2° of the. We claim as inventions, joint improvements made here as not mentioned in the foregoing specification the following things. 1° The use and application of the globe or cover in the manner and for the purposes before mentioned. — 2° The manner of fixing the globe or cylinder as hereinafter described and especially the placing of the globe or cylinder in the escape heat of the boiler and other heat as before stated & the iron or copper tube which transmits heat right into the globe or cylinder as described from its heat furnace. — 3° The method of changing the direction & application of the steam to produce motion in different directions as before described. — 4° The producing of a current or current of steam with the expense of fuel or machinery and nevertheless danger of explosion than many of the methods heretofore practised or known.

Hebrides.

Dated the sixteth day January AD 1854
